UNITED STATES PATENT OFFICE.

HERBERT WILLIAM BAMBER, OF LONDON, ENGLAND, ASSIGNOR TO MAURICE STEIN-MAN BEZENCENET, OF LONDON, ENGLAND.

GAS PRODUCER FOR USE IN AUTOMOBILES AND THE LIKE.

Application filed November 23, 1921. Serial No. 517,244.

To all whom it may concern:

Be it known that I, HERBERT WILLIAM BAMBER, a subject of the King of Great Britain, and a resident of London, England, 5 have invented certain new and useful Improvements in Gas Producers for Use in Automobiles and the like, of which the following is a specification.

This invention relates to gas producers 10 and particularly to that kind of gas producer employed for obtaining the fuel supply for internal combustion engines as used for automobiles, small marine craft, portable sets for agricultural purposes, and the 15 like.

Owing to the comparatively small size of 20 such producers and the necessity of keeping down the aggregate weight of the apparatus it is essential that the parts susceptible to 25 wear and tear or over heating should be readily replaceable and the object of the present invention is to obtain this desirable end besides simplifying the general construction and assemblage of the several parts.

For this purpose a producer constructed 30 in accordance with my present invention comprises an inner steel chamber preferably of cylindrical form with or without a refractory lining that serves as the producer, or the inner chamber may be made of a refractory material without the enclosing steel chamber. This steel or inner chamber is provided with an external flange situated 35 near its top that rests on a flange provided on the external shell or casing whereby an annular space or air passage is formed that surrounds the producer. To the base of this external shell or casing is affixed by 40 any suitable means the ash pit which supports the grate with the upper surface of which the inner refractory chamber contacts. The ash pit is provided with the usual door for the removal of ashes. The 45 grate is mounted on an axis or spindle situated at the opposite side of the ash-pit from the door and provided with means for lowering the said grate into the ash pit in order to facilitate the removal of clinker and 50 ashes from the interior of the furnace. The spindle is preferably made hollow or tubular and at the outside end thereof may be affixed a float chamber which is supplied with water by a flexible pipe connection 55 with the water storage tank, a suitable pipe

connection being made with said tubular spindle to the small steam generator or boiler which is formed as an integral part of the grate. By this means a constant level of water is maintained in the boiler. A lever is provided by means of which the grate can be raised or lowered as may be required suitable retaining mechanism being employed for keeping the grate in its normal raised position adjacent to the base of the 60 producer. The upper part of the external shell or casing carries the usual feed hopper and the space between the inner chamber and the outer shell, above the flanges by which the two are held together, forms an 65 annular collecting chamber for the gas issuing from the producer and the outlet conduit is fixed to this part of the shell to convey the gas to the scrubber or elsewhere as 70 the case may be.

In order that my invention may be readily understood in the annexed drawing, there is illustrated a producer with my improvements applied thereto in which Figure 1 is a vertical section, Figure 2 a similar section 75 as viewed from left to right of Figure 1 and Figure 3 is a vertical section of a modified form of construction similar letters of reference in all the figures relating to like parts.

Referring now to Figures 1 and 2 the producer comprises an inner steel chamber *a* of cylindrical form with a refractory lining *b* that rests on an internal flange *c*. The inner chamber *a* is provided with an external flange *d* that rests on and is bolted to the 80 top flange *e* of the shell or casing *f* in such a manner as to form therewith the annular air space *g* surrounding the producer. The base of the external shell or casing *f* is secured to the ash pit *h* by any suitable means 85 as for example as shown by resting in the annular groove *i* at the top of the ash pit *h* and secured therein by bolts or set screws *j*. The ash pit *h* is provided with the usual door *k* for the removal of ashes and the 90 grate *m* contacts with the lower end of the inner chamber *a* and is swivellably mounted on the axis or spindle *n* supported by the bracket *o* in such a manner that it can be lowered in the ash pit *h* as shown in dotted 95 lines in Figure 2 the operation being effected by the manipulation of the lever *p* whilst the fore part of the grate is retained in its 100 normal working position by the strut *q* pivotally fixed to the front of the grate *m*. 105

The spindle *n* is preferably made hollow or tubular and at the outside end thereof may be affixed a float chamber of any convenient and well known type for the maintenance of a constant level of water within the boiler or vaporizer *r* the service thereto being established by the pipe *s* and the connection to the float chamber (not shown in drawing) by the flexible pipe *t*.
10 The boiler shown in the drawing is of the type described in U. S. Patent 1,420,570, but any other form of vaporizer may be employed. The upper part of the external shell or casing *f* carries the usual feed hopper *u* and the space between the inner chamber *a* and the superstructure *v*, above the flanges *d* and *e* by which the parts are held together, forms an annular collecting chamber *w* for the gas issuing from the producer 15 which may be led away therefrom by a conduit not shown fixed to the outlet *y* leading to the scrubber or elsewhere as the case may be.

In the modification illustrated in Figure 25 3 it will be observed that the inner refractory lining has been dispensed with and it will be obvious that instead of a metal interior the producer may be of refractory material unsupported by a metallic casing.
30 It will be understood from the foregoing description that presuming the removal of the feed hopper *u* and superstructure *v* the inner chamber *a* together with its lining *b*, when the latter is employed, can be removed bodily without dis-

turbing the other parts of the producer. Similarly the base or ash pit *h* together with the grate *m* can be entirely removed from the producer by the removal of the few bolts *j* used to join the shell *f* and ash pit *h* together so that the renewal of the various parts can be effected very expeditiously, if and when required.

Air is injected at *A*, into the annular space *g* between the wall of the chamber *a* and the shell or casing *f*, passes downwardly into ash pit whence it makes its way upwardly through the grate bars and mixed with steam passes through the glowing incandescent fuel in the chamber *a*.

What I claim is:—

A gas producer comprising an inner generating chamber provided with a single external flange at its upper end, an outer metallic casing surrounding said generating chamber and an ash pit disposed below said chamber, the upper end of said casing having a flange that supports, and is removably secured to, said external flange and the lower end of said casing resting in an annular groove in the top of the ash pit, a grate swivellably mounted on a tubular axis within said ash pit and contacting with the lower end of the inner generating chamber, a vaporizer situated beneath said grate and a pipe connecting said tubular axis with the vaporizer.

In testimony whereof I affix my signature.

HERBERT WILLIAM BAMBER.
